SEALING DEVICE

Winfred M. Brooks, West Orange, N. J., assignor to E. J. Brooks Company, Newark, N. J., a corporation of New Jersey

Application September 22, 1949, Serial No. 117,219

5 Claims. (Cl. 292—322)

1

This invention relates to sealing devices, particularly, though not exclusively, of that type which is intended to be applied to meat or fowl. The main object and feature of the invention is to provide a construction that will assure the proper closing of the seal even if the parts are somewhat misdirected during the closing action, and which will also tend to prevent laceration of the fingers of the operator who closes the seal.

In the accompanying drawings the invention is shown in several concrete and preferred forms, to wit, Figs. 1 to 7 inclusive show one form of the invention, Figs. 8 and 9 a second form, Figs. 10 to 14 inclusive a third form, and Figs. 15 to 17 inclusive a fourth form of the invention.

Fig. 1 is a plan view of the blank from which the seal is formed;

Fig. 2 is an edge view of Fig. 1;

Fig. 3 is a view in side elevation of the blank shown in Fig. 1 bent up preparatory to its use in the sealing operation;

Fig. 4 is a view looking in the direction of arrow 4 of Fig. 3;

Fig. 5 is a sectional view substantially on the plane of line 5—5 of Fig. 3;

Fig. 6 is a sectional view substantially on the plane of line 6—6 of Fig. 7;

Fig. 7 is a sectional view showing the seal in its closed position;

Fig. 8 is a view similar to Fig. 7 but showing a different form of the invention;

Fig. 9 is a sectional view substantially on the plane of line 9—9 of Fig. 8;

Fig. 10 is a view similar to Fig. 1 but showing a modified form of the invention;

Fig. 11 is a sectional view similar to Figs. 7 and 8 but showing the form of the invention of Fig. 10;

Fig. 12 is a sectional view substantially on the plane of line 12—12 of Fig. 11;

Fig. 13 is a front view of the seal of Figs. 10, 11 and 12 before the seal is closed;

Fig. 14 is a front view showing the seal of Fig. 13 in its closed position;

Fig. 15 is a plan view of the blank from which the seal is made but showing a modified form of the invention;

Fig. 16 is a view similar to Fig. 13 but showing the construction of the seal of Fig. 15; and

Fig. 17 is a view similar to Fig. 14 showing the seal of Fig. 16 in its closed position.

Referring first to Figs. 1 to 7, inclusive, 20 and 21 indicate two bendably connected main sections of sheet material. Main section 20 has an inner curved surface 20^a and is provided with a tongue 22 formed integrally therewith and bent

inwardly thereover in spaced relation thereto. Tongue 22 has an unbent portion 23 severed from the tongue but connected at its base to main section 20 at the line of bending of tongue 22 to thereby provide an opening 24 in said tongue adjacent its line of bending. Said unbent portion 23 has an upper curved surface 23^a that forms a continuation of inner curved surface 20^a and forms an outboard extension of main section 20 and constitutes a combined finger guard and auxiliary deflecting surface. 25 indicates a detent on tongue 22 lying bent toward the inner surface of main section 20. Main section 21 is provided with a prong 26 (usually but not necessarily in the form of a piercing element), integrally formed therewith and bent toward main section 20 to enter opening 24 of tongue 22 when the two main sections are bent toward each other. 27 indicates an inwardly projecting spur on prong 26 adapted to engage detent 25 when the seal is closed. It will now be understood that, when main sections 20 and 21 are properly bent toward each other in closing the seal, prong 26 will usually enter opening 24 and will then be deflected by the inner surface 20^a of main section 20 to engage detent 25 thereby lifting it and tongue 22 and placing the parts under tension. After spur 27 has passed beyond detent 25, the parts may be released and the return movement of the parts will cause spur 27 to engage detent 25 so that the seal cannot be opened by retracting prong 26. If, however, in the act of closing the seal, prong 26 is outwardly misdirected, then it will engage upper curved surface 23^a of member 23 thereby causing prong 26 to enter opening 24 and will be thereafter deflected as previously described by inner surface 20^a of main section 20. It will be understood that outboard extension 23 not only directs prong 26 into opening 24, but also acts as a guard protecting the fingers of the operator.

In the modification shown in Figs. 8 and 9, the construction of the seal is substantially like that described in Figs. 1 to 7 inclusive, and the same reference characters will apply with this exception: that spur 27^a on prong 26, instead of engaging a detent like 25, will engage the free end 22^a of tongue 22.

The construction shown in Figs. 10 to 14 inclusive is substantially the same as that previously described in connection with Figs. 1 to 7 inclusive and the same reference characters will apply with these exceptions: prong 26^b is devoid of a spur but is provided with a narrow neck 28 at its base where it is connected to main section 21. Tongue 22^b has its opening 24^b so

shaped as to be relatively wide at one end 30 and with shouldered formation 31 diminishes in width toward its other end.

In the modification shown in Figs. 15 to 17, there is disclosed substantially the same construction as is described in the modification shown in Figs. 10 to 14 inclusive except that prong 26^c is connected at its base to main section 21 by a narrow neck portion 29 having square shoulders in contradistinction to the curved formation 28 shown in Fig. 10. Opening 24^c in tongue 22^c is relatively wide at one end 32 and with shouldered formation 33 diminishes in width toward its other end.

It will be noted that, in the two modifications of the invention comprised respectively by Figs. 10 to 14 inclusive and Figs. 15 to 17 inclusive, there are no interlocking spurs and detents on the prong and tongue of the forms of the invention such as are shown in Figs. 1 to 7 inclusive or in Figs. 8 and 9. It has been found that these spurs and detents may be omitted if a narrow neck portion such as 28 or 29 is provided, because in closing the seal these narrow neck portions are bent beyond their limits of elasticity so that in attempting to open the seal the metal of the prong at its line of bending will be apt to break thereby leaving evidence that the seal has been tampered with. Or, if it be attempted to jiggle the prong sideways to withdraw it without unbending it, the narrow neck portions 28 or 29 will encounter the square shoulders 31 or 33 of openings 24^b or 24^c and thus prevent withdrawal of the prong. It should be noted that neck portions 28 or 29 must be at the very base of prongs 26^b or 26^c, since otherwise difficulty will be encountered in closing the seal, as any intermediate reduced portion will be apt to catch in square shoulders 31 or 33 of openings 24^b or 24^c and thus prevent closing 40 of the seal.

I claim:

1. In a seal having two bendably connected main sections of sheet material, the combination with one of said main sections, provided with an inner curved surface, of a tongue formed integrally with said one main section and bent inwardly thereover in spaced relation thereto, said tongue having an unbent portion severed from the tongue but connected at its base to the one main section at the line of bending of said tongue to thereby provide an opening in said tongue adjacent its line of bending, said unbent portion having an upper curved surface forming a continuation of the inner curved surface, and an outboard extension of said one main section and constituting a combined finger guard and auxiliary deflecting surface; and in combination with the other of said main sections of a prong integrally formed therewith and bent toward the first-mentioned main section to enter the opening in the tongue of said first-mentioned main section when the two main sections are bent toward each other, and said prong of the second main section adapted to be deflected by the inner wall of said first-mentioned main section or, if outwardly misdirected in bending the two main sections toward each other, to be deflected first by the combined finger guard and auxiliary deflecting surface of said first-mentioned main section so as to enter the opening in the tongue of said first-mentioned main section and thereafter to be deflected by the inner wall of said first-mentioned main section.

2. In a seal having two bendably connected

main sections of sheet material, the combination with one of said main sections, provided with an inner curved surface, of a tongue formed integrally with said one main section and bent inwardly thereover in spaced relation thereto, said tongue having an unbent portion severed from the tongue but connected at its base to the one main section at the line of bending of said tongue to thereby provide an opening in said tongue adjacent its line of bending, said unbent portion having an upper curved surface forming a continuation of the inner curved surface, and an outboard extension of said one main section and constituting a combined finger guard and auxiliary deflecting surface, said tongue having further a detent lying bent toward the inner surface of said main section; and in combination with the other of said main sections of a prong integrally formed therewith and bent toward the first-mentioned main section to enter the opening in the tongue of said first-mentioned main section when the two main sections are bent toward each other, and said prong of the second main section adapted to be deflected by the inner wall of said first-mentioned main section or, if outwardly misdirected in bending the two main sections toward each other, to be deflected first by the combined finger guard and auxiliary deflecting surface of said first-mentioned main section so as to enter the opening in the tongue of said first-mentioned main section and thereafter to be deflected by the inner wall of said first-mentioned main section, and an inwardly projecting spur on the prong of said second-mentioned main section to engage the detent on the tongue of said first-mentioned main section.

3. In a seal having two bendably connected main sections of sheet material, the combination with one of said main sections, provided with an inner curved surface, of a tongue formed integrally with said one main section and bent inwardly thereover in spaced relation thereto, said tongue having an unbent portion severed from the tongue but connected at its base to the one main section at the line of bending of said tongue to thereby provide an opening in said tongue adjacent its line of bending, said unbent portion having an upper curved surface forming a continuation of the inner curved surface, and an outboard extension of said one main section and constituting a combined finger guard and auxiliary deflecting surface; and in combination with the other of said main sections of a prong integrally formed therewith and bent toward the first-mentioned main section to enter the opening in the tongue of said first-mentioned main section when the two main sections are bent toward each other, and said prong of the second main section adapted to be deflected by the inner wall of said first-mentioned main section or, if outwardly misdirected in bending the two main sections toward each other, to be deflected first by the combined finger guard and auxiliary deflecting surface of said first-mentioned main section so as to enter the opening in the tongue of said first-mentioned main section and thereafter to be deflected by the inner wall of said first-mentioned main section, and an inwardly projecting spur on the prong of said second-mentioned main section to engage the free end of the tongue on said first-mentioned main section.

4. In a seal having two bendably connected main sections of sheet material, the combina-

tion with one of said main sections, provided with an inner curved surface, of a tongue formed integrally with said one main section and bent inwardly thereover in spaced relation thereto, said tongue having an unbent portion severed from the tongue but connected at its base to the one main section at the line of bending of said tongue to thereby provide an opening in said tongue adjacent its line of bending, said opening relatively wide at one end and with shoul- dered formation diminishing in width toward its other end, said unbent portion having an upper curved surface forming a continuation of the inner curved surface, and an outboard extension of said one main section and constituting a combined finger guard and auxiliary deflecting surface; and in combination with the other of said main sections of a prong integrally connected by a narrow neck portion at its base to said second main section, said prong bent toward the first-mentioned main section to enter the opening in the tongue of said first-mentioned main section when the two main sections are bent toward each other, and said prong of the second main section adapted to be deflected by the inner wall of said first-mentioned main section or, if outwardly misdirected in bending the two main sections toward each other, to be deflected first by the combined finger guard and auxiliary deflecting surface of said first-mentioned main section so as to enter the opening in the tongue of said first-mentioned main section and thereafter to be deflected by the inner wall of said first-mentioned main section.

5. In a seal having two bendably connected main sections of sheet material, the combination with one of said main sections, provided with an inner curved surface, of a tongue formed integrally with said one main section and bent inwardly thereover in spaced relation thereto,

5 10 15 20 25

said tongue having an unbent portion severed from the tongue but connected at its base to the one main section at the line of bending of said tongue to thereby provide an opening in said tongue adjacent its line of bending, said unbent portion having an upper curved surface forming a continuation of the inner curved surface, and an outboard extension of said one main section and constituting a combined finger guard and auxiliary deflecting surface; and in combination with the other of said main sections of a prong integrally formed therewith and bent toward the first-mentioned main section to enter the opening in the tongue of said first-mentioned main section when the two main sections are bent toward each other, and said prong of the second main section adapted to be deflected by the inner wall of said first-mentioned main section or, if outwardly misdirected in bending the two main sections toward each other, to be deflected first by the combined finger guard and auxiliary deflecting surface of said first-mentioned main section so as to enter the opening in the tongue of said first-mentioned main section and thereafter to be deflected by the inner wall of said first-mentioned main section, and means to prevent retraction of said prong when the seal is in closed position.
